FLOTATION

Philip M. Frantz and William M. Bertholf, Pueblo,
Colo., assignors to The Colorado Fuel and Iron
Corporation, Denver, Colo., a corporation of
Colorado

Application December 17, 1941, Serial No. 423,342

5 Claims. (Cl. 209—168)

This invention is concerned with froth flotation and provides an improved skimmer for removing froth accumulating in a flotation machine. The invention is particularly applicable to the skimming of a fast-forming froth of coal and the like, but may be employed advantageously in the removal of all types of mineral-bearing froths.

In froth flotation, an aqueous pulp of a comminuted mineral aggregate is subjected to aeration or the like in the presence of one or more flotation reagents with the result that a mineral-bearing froth is formed on top of the pulp. Some flotation froths are such that they overflow from a discharge lip at or near the top of the pool of pulp without aid. However, in many cases it is necessary to skim the froth. When flotation froths are very viscous and do not flow readily, it is desirable to skim them. Fragile froths, which tend to break readily, advantageously are skimmed from the top of the pulp before the mineral floated has an opportunity to sink back into the pulp. Thirdly, when the mineral floated is a large proportion of the total ore, the froth may form so fast that skimming is necessary to obtain maximum capacity for a given flotation machine.

It has been proposed heretofore to push froth over the discharge lip of a flotation machine with positively driven wheels mounted on a substantially horizontal axis and equipped with one or more flat paddles that skim the froth from the top of the pulp. However, such paddle wheels are not suitable for skimming all types of froth. If the flat paddles are rotated at the high speed required when a fast-forming froth is to be skimmed, violent splashing and tossing may occur. In such case, some of the froth is broken so that its mineral content has to be re-floated. Even at slow speeds, the action of flat paddles of the type employed heretofore is uneven. Such paddles slap the froth and tend to break it with consequent reduction in the capacity of the flotation machine.

The deleterious effect of the flat paddles is particularly serious in coal flotation where the amount of froth formed is very large in proportion to the volume of pulp treated. In such operations froth forms so rapidly that the paddle-type skimmer must be revolved rapidly in order to keep the flotation machine clear and this high speed of paddle rotation brings about a serious destruction of froth.

As the result of our investigations, we have developed a novel skimmer adapted to operate in conjunction with a froth over-flow for a froth flotation machine and which is much more efficient than the flat paddle type. It comprises a helical paddle (preferably of steep pitch) rotatably mounted on an approximately horizontal axis above the pulp pool of a froth flotation ma-

chine with its lower edge in the neighborhood of the level of the pool, i. e., so that the periphery of the rotating blade scrapes substantially horizontally at or near the pulp level. In the preferred form, the axis of rotation is horizontal and the paddle comprises a pair of blades of uniform width measured from their periphery to the axis. The paddle is positively driven and should be mounted reasonably close to the discharge or over-flow of the flotation machine and preferably substantially parallel thereto, so that as the helix is rotated it cuts gradually into the froth bed overlying the pool beginning at one end and continuously pushes the froth over the discharge.

10 In short, our invention contemplates the combination in a froth flotation machine having a flotation chamber adapted to contain a pool of liquid underlying a bed of mineral-bearing froth which comprises a skimming member in the form of a helical blade rotatably mounted on an approximately horizontal axis above the pool, a froth overflow on the chamber adjacent the skimming member but below its axis, and means for positively rotating the helical blade about its axis.

15 The helical skimmer of our invention, in its preferred form, resembles a double-thread screw with a very steep pitch or a lawn mower equipped with a single blade that extends from the shaft to the periphery.

20 25 These and other features of our invention will be more thoroughly understood in the light of the following detailed description taken in conjunction with the accompanying drawing in which:

30 35 Fig. 1 is a fragmentary elevation, partly in section, of the spitzkasten or frothing chamber of a flotation machine equipped with an improved skimmer of our invention;

35 40 Fig. 2 is a longitudinal elevation of the skimmer of Fig. 1; and

45 45 Fig. 3 is a plan view of the skimmer.

Referring to the drawing, it will be observed that the spitzkasten 10 of a froth flotation machine is filled with an aqueous ore pulp 11 to a level 12 slightly below the top of a discharge lip 13 at the top of the spitzkasten. When the pulp in the machine is aerated, a body of froth 14 is formed on the top of the pulp and this froth is pushed over the discharge lip by a skimmer mechanism 15. The skimmer mechanism comprises a rotatably mounted horizontal shaft 16 that is disposed substantially parallel to the discharge lip. A helical paddle 17 of screening, sheet metal or the like, is fastened concentrically around the shaft, the pitch of the helix being such that it makes about one-third of a complete turn about the shaft in the length of the helix, which extends lengthwise of the flotation machine. The shaft is positively rotated in a counterclockwise direction (as viewed in Fig. 1) by means of a

pulley 18 provided with a belt 19 or other conventional driving means.

Our preferred helical skimmer has two blades 17A, 17B mounted opposite each other on the shaft, so that it resembles a double-thread screw on which the edge of each blade corresponds to a thread of the screw. However, the skimmer may be provided with more than two blades, somewhat in the manner of a lawn mower, but ordinarily this is unnecessary and we prefer to employ a skimmer with a single blade.

As indicated above, the pitch of the helix preferably is quite steep. Tests indicate that optimum results are obtained when the skimmer plate makes about one complete turn around its shaft in a length of 36", or approximately one-third of a complete turn in its own length, say, about 12". The rule as to the number of turns in terms of length appears to be applicable, at least within broad limits, irrespective of the width of the plate. In other words, a plate having a radius of 6" should have about the same turns per unit of length as a plate having a radius of, say, 12".

Comparative tests with skimmers of the conventional flat paddle type show the great superiority of the skimmer of our invention. In the tests, the flat paddle skimmer was exactly the same as the helical skimmer in dimension, location and material except that in the helical skimmer the plate was twisted about its axis with a pitch of about one-third of a turn in 12". The two skimmers were subjected to tests under identical conditions in the skimming of a coal-bearing froth produced with a "mineral separation" type of flotation machine commonly used for coal flotation and provided with a double discharge.

It was found that the flat paddle type of skimmer caused excessive splashing and tossing of the froth when it was operated with a peripheral speed (measured at the tips of the paddle) exceeding about sixty feet per minute. Moreover, the skimming action of the flat paddle was somewhat intermittent so that the froth came to rest between revolutions of the paddle with a resultant slapping action which tended to break the froth. The broken froth represented mineral which had to be re-floated with a consequent decrease in the capacity of the flotation machine.

In contrast, the helical skimmer of our invention could be run at peripheral speeds more than twice the maximum of the flat paddle without causing undue splashing. Moreover, the skimming action of the helix was much smoother since it tended to cut into the froth bed gradually from side to side. There was, therefore, a minimum of froth destruction and a minimum of required re-flotation.

It was found that the helical skimmer could be operated over a considerable velocity range with good results. Thus, a helical skimmer having a radius of about 6" could be operated over a velocity range of from about 16 R. P. M. to about 85 R. P. M.

In the tests, it was established that the helical paddle rotating at the same speed as the conventional flat paddle would remove approximately twice as much froth in a given time, or, otherwise expressed, would remove a given quantity of froth in about one-half the time required by the flat paddle. However, because the helical blade can be rotated at speeds approximately twice the maximum of the flat paddle without bringing about serious splashing and tossing, a helical

blade operating at its maximum speed will remove about three times as much froth in a given time as a flat paddle of equal size operating at its maximum speed.

5 The tests indicate that in the flotation of a material like coal where the concentrates amount to a large proportion, say 75 to 85% of the feed, and the flotation time is short, the use of helical paddles will nearly double the capacity of a given 10 flotation machine, for example a "M. S." machine with double froth discharge.

15 The helical blades of our invention may be made of a variety of materials. Smooth sheet metal and screen cloth are both satisfactory, although the sheet metal is preferred. In the flotation of coal, or in other froth flotation processes in which the skimmer may be subjected to corrosive influences, we prefer to employ a helical blade of stainless steel or other corrosion-resistant metal.

20 We claim:

1. In a froth flotation machine having a flotation chamber adapted to contain a pool of liquid underlying a bed of mineral-bearing froth, the combination which comprises a skimming member in the form of a helical blade rotatably mounted on an approximately horizontal axis above the pool, a froth over-flow on the chamber adjacent the skimming member and below its 25 axis, and means for positively rotating the helical blade about its axis.

2. In a froth flotation machine having a flotation chamber adapted to contain a pool of liquid underlying a bed of mineral-bearing froth, the combination which comprises a skimming member in the form of a steeply pitched helical blade 30 rotatably mounted on an approximately horizontal axis above the pool, a froth over-flow on the chamber adjacent the skimming member but below its axis, and means for positively rotating the helical blade about its axis.

3. In a froth flotation machine having a flotation chamber adapted to contain a pool of liquid underlying a bed of mineral-bearing froth, the combination which comprises a froth over-flow 35 on the chamber, a skimming member in the form of at least one helical blade rotatably mounted on an approximately horizontal axis above the pool and the overflow and approximately parallel to the froth over-flow, and means for positively 40 rotating the helical blade about its axis.

4. In a froth flotation machine having a flotation chamber adapted to contain a pool of liquid underlying a bed of mineral-bearing froth, the combination which comprises a skimming member 45 in the form of a pair of helical blades rotatably mounted opposite each other on an approximately horizontal axis above the pool, a froth over-flow on the chamber adjacent the skimming member but below its axis, and means for positively 50 rotating the helical blade about its axis.

5. In a froth flotation machine having a flotation chamber adapted to contain a pool of liquid underlying a bed of mineral-bearing froth, the combination which comprises a skimming member 55 in the form of at least one helical blade rotatably mounted on an approximately horizontal axis above the pool and so pitched that the blade makes approximately one-third of a turn about its axis in its length, a froth over-flow on the chamber adjacent the skimming member but below its axis, and means for positively 60 rotating the helical blade about its axis.
